UNITED STATES PATENT OFFICE

JOSEPH VON ALT, OF CLEVELAND, OHIO

DESIGN FOR AN ILLUMINATED HOUSE NUMBER CASING OR SIMILAR ARTICLE

Application filed January 16, 1932. Serial No. 42,506. Term of patent 7 years.

To all whom it may concern:

Be it known that I, JOSEPH VON ALT, a citizen of the United States, residing at Cleveland, in the county of Cuyahoga and State of Ohio, have invented a new, original, and ornamental Design for an Illuminated House Number Casing or Similar Article, of which the following is a specification, reference being had to the accompanying drawing, forming part thereof, and in which drawing,

I claim:

The ornamental design for an illuminated house number casing or similar article, as shown.

JOSEPH VON ALT.
